UNITED STATES PATENT OFFICE.

WILLIAM A. MURRAY, OF WASHINGTON, DISTRICT OF COLUMBIA.

COPYING-BATH.

SPECIFICATION forming part of Letters Patent No. 788,787, dated May 2, 1905.

Application filed March 10, 1904. Serial No. 197,539.

To all whom it may concern:

Be it known that I, WILLIAM A. MURRAY, a citizen of the United States, residing at Washington, in the District of Columbia, have invented new and useful Improvements in Copying-Baths, of which the following is a specification.

This invention relates to copying-baths; and the primary object of the same is to provide a device of this class having a simplified construction and capable of holding a number of pads or cloths and also to contain sufficient moisture to dampen any number of pads or cloths and maintain the latter in condition for use for a considerable length of time.

A further object of the invention is to provide a copying-bath having a top portion or cover pivotally held therein and capable of being adjusted vertically as well as readily removed and applied with respect to the body of the bath.

A still further object of the invention is to so organize the several parts or elements of the bath that they will be rendered readily accessible, convenient in operation, strong, and durable, and including means for storing a great number of pads or cloths.

With these and other objects and advantages in view the invention consists in the construction and arrangement of the several parts, which will be more fully hereinafter set forth.

In the drawings, Figure 1 is a longitudinal vertical section of a copying-bath embodying the features of the invention and showing the top portion or cover open. Fig. 2 is a similar view showing the top portion or cover closed. Fig. 3 is a transverse vertical section on the line 3 3, Fig. 2. Fig. 4 is a detail perspective view of a part of the upper portion of the body.

Similar numerals of reference are employed to indicate corresponding parts in the several views.

The numeral 1 designates a body of considerable depth and having a box or tank configuration and preferably constructed from non-corrosive metal. The body is provided with an upper open end, and therearound is formed a beaded rim 2 to strengthen the same and

effect a neat and smooth finish. The body is divided by a horizontal partition 3, which is located near the bottom 4 to form a drawer or slide compartment 5, in which is arranged a drawer or slide 6, with opposite packed ends 7, formed by bending the terminals of the said drawer or slide upwardly and inwardly over wood strips 8, which give the drawer or slide ends sufficient rigidity to maintain the said drawer in form and facilitate movement thereof into and out of the compartment 5. For convenience in operating the drawer or slide 6 a knob or analogous pull device 9 is attached to the outer end thereof, and said drawer or slide is formed without sides, so that pads which are held between the ends 7 may be readily accessible and easily withdrawn from or disposed in the said drawer or slide. The bath is portable, and to facilitate movement thereof from one position to another grips 10 are secured to the upper portions of the ends of the body and in the present instance consist of rings, though other devices may be used. Arranged on the partition 3 is a moisture-absorbing pad 11, of plaster-of-paris, held in a metallic tray or pan 12, which is fixed to said partition. This pad 11 terminates a considerable distance from the rear end of the body 1, and the plaster-of-paris extends upwardly flush with the upper edge of the pan or tray. Near its rear end the opposite sides of the body are formed with vertical slots 13, communicating with outstanding upright tubular guides or barrels 14, which are fully open at the top and closed at the bottom and which constitute covering means for the slots. These guides have their upper open ends surrounded by a strengthening-rim wire 15.

The top portion or cover of the bath consists of a metallic tray, pan, or shallow box 16, in which is secured a moisture-absorbing pad 17 of plaster-of-paris. In view of the fact that the top portion or cover must be frequently moved under certain operations with respect to the pad 11 any tendency toward loosening or disintegration of the pad 17 must be obviated without in the least detracting from the absorbent characteristics of the material of which said pad is composed.

The preferred securing means shown consists of a series of metallic straps 18, extending longitudinally of the tray or pan 16 at a distance from the open side of the latter, which exposes the pad 17. Engaging the said straps 18 are cross or transverse straps 19, which are arranged alternately against opposite sides of the said straps 18. In the present instance three straps 18 and four straps 19 are used 10 to form the securing means for the pad 17; but it will be understood that this number may be varied at will. The top portion or cover of the bath, as set forth, and clearly shown by Figs. 1, 2, and 3, has a pivotal or 15 hinge movement in the body through the medium of a pintle or hinge-rod 20, extending transversely through the rear extremity thereof and continued beyond the opposite sides of the tray or pan 16 through the slots 13, 20 the opposite portions of the pintle or rod engaging the said slots being formed with flat faces 21 to prevent wobbling or oscillation of the top portion or cover and also to facilitate the withdrawal and accurate disposition of 25 the said top portion or cover in the body. The opposite extremities of the pintle or rod 20 are bent upwardly and extend through the central portion of the guides or barrels 14, said extremities being screw-threaded to provide adjusting-stems 22, which are engaged by upper adjusting-nuts 23, having milled 30 heads 24, and lower bearing enlargements 25 formed with circumferential shoulders 26, which rest on the rims of the guides or barrels 14. The enlargements 25 also have depending extensions 27, which rotatably fit into the upper open ends of the guides or barrels and maintain the stems 22 in central relation in said guides.

40 From the foregoing it will be readily seen that the top portion or cover carrying the pad 17 may be quickly raised or lowered, or removed from and inserted in the body 1 without necessitating a disconnection of the nuts 23 from the stems 22 or a separation of the rod or pintle 20 from the top portion or cover. Moreover, the top portion or cover carrying the pad 17 may be vertically adjusted with 45 respect to the pad 11 in accordance with the number of textile copying pads or cloths arranged between the two pads.

50 The use of the horizontal partition 3 also provides for the formation of a moisture-containing receptacle, a space being formed between the sides and front end of the tray or pan 12, and the adjacent walls of the body provide a water-receiving space. Though plaster-of-paris has been described as the preferred material of which the pads 11 and 17 55 are composed, it will be understood that other materials or compositions may be adopted, if desired.

60 By forming the slots in the opposite sides of the body near the rear end of the latter and having said slots of considerable ver-

tical extent the top portion or cover of the bath can be conveniently supported when open by resting against the upper edge or rim of the rear end of the body 1, as clearly shown by Fig. 1. By this means the said top portion 70 or cover of the bath will always be in convenient position to readily close, and when open the weight strain of said cover is materially removed from the pintle or rod 20. By holding the cover or top portion when open 75 in the body 1, as just set forth, projection thereof in an inconvenient manner materially beyond the confines of the body is prevented, and at the same time said cover is always within easy reaching distance. As a simple 80 means for facilitating raising and lowering operations of the top portion or cover of the bath the free end of the latter is provided with a grip or ring 28. By forming the tray 12 of less dimensions than the body 1 and providing a space entirely around the said tray the excess moisture from the pad 11 is permitted to overflow into said space and render the operation of the device more effective 85 with respect to the cloth pads interposed between the plaster-of-paris pads 11 and 17. In preparing the copying-bath for use the pads 11 and 17 are moistened to prevent them from drying out and taking up the moisture from the cloth pads interposed therebetween too 90 quickly.

95 The proportions and dimensions of the parts of the bath may be modified at will, and all the parts will be so joined as to obstruct the formation of leaking openings or apertures. 100

Having thus fully described the invention, what is claimed as new is—

1. In a copying-bath, a body having the opposite sides near one end vertically slotted, a pad in the body, inclosing means over the 105 slots, a cover carrying a pad, a pivot device extending through one end of the cover and also through the slots, said pivot device having upwardly-projecting screw-shanks in the inclosing means, and adjusting devices engaging the screw-shanks and bearing on the upper ends of the inclosing means. 110

2. In a copying-bath, a body having slots in the opposite sides near one end opening through the top thereof, tubular guides arranged over the slots, a cover having a pivot device extending therethrough and also projecting through the slots and upwardly through the guides, and adjusting devices engaging the portions of the pivot device projecting 115 upwardly through the guides. 120

3. In a copying-bath, a body having slotted sides, a cover movable in the body and provided with pivot means projecting through the slotted sides of the body and formed with 125 upwardly-extending shanks, and adjusting devices engaging the said shanks.

4. In a copying-bath the combination of a body having slotted sides, a cover movable in the body, pivot means movably extending 130

- through the cover and the slotted sides of the body and having upwardly-projecting extremities exterior of the body sides, and adjusting devices engaging said extremities.
- 5 5. In a copying-bath, a body having opposite sides near one end provided with vertical slots opening through the upper edges of said sides, covering means for the slots, a cover removably and adjustably located within the body, and pivot means for the cover freely removable from the body upwardly through the slots without detaching said means, the cover when open being partially projected downwardly into the body and supported by one end of the latter.
- 10 6. In a copying-bath, a body having vertical slots therein near one end opening through the upper edge thereof, a cover in the body, and pivot means loosely projecting through one end of the cover and outwardly beyond opposite sides of the latter through the said slots, the pivot means being held against rotation and the cover freely movable on said means, and said pivot means also freely withdrawable from and applicable to the body sides without disengaging the same from the cover.
- 15 7. In a copying-bath, a body, a cover adjustably mounted in the body, pivot means loosely engaging the cover, and adjusting devices on a portion of the pivot means, the said pivot means and adjusting devices being freely removable from and applicable to the body without separating them from the cover.
- 20 8. In a copying-bath, a body, a cover movable in the body, and pivot means for the cover having adjusting devices, the pivot means having upwardly-projecting devices at the ends to receive adjusting devices which are held in upright position at opposite sides of the body and operative from the top of the latter.
- 25 9. In a copying-bath, the combination of a body having slots in the opposite sides thereof, a cover, a pivot device extending through the cover near one extremity and having opposite flat faces to engage the slots in the sides of the body and also provided with projecting screw-stems, and means for engaging said stems to adjust the cover in the body.
- 30 10. In a copying-bath, the combination of a body having slots in the opposite sides thereof, a cover, a pivot device extending through the cover near one extremity thereof and having opposite faces to engage the slots in the sides of the body and also provided with up-
- wardly-projecting screw-stems at an angle thereto, and means for engaging said stems to adjust the cover in the body.
11. In a copying-bath, the combination with a body having slots in the opposite sides thereof, tubular guides applied to the body over the slots and having upper open ends, a cover mounted in the body, a pivot device extending through one extremity of the cover and also projecting through the slots and terminating in screw-stems rising through the guides, and adjusting-nuts on the upper ends of the guides engaging the said screw-stems. 60
12. In a copying-bath, the combination with a body having slots in the opposite sides thereof, of tubular guides applied to the body over the slots and having upper open ends, a cover mounted in the body, a pivot device extending through one extremity of the cover and also projecting through the slots in the body 65 and terminating in screw-stems rising through the guides, and adjusting-nuts on the upper ends of the guides having depending projections entering the latter. 70
13. In a copying-bath, the combination with a body having slots in the opposite sides thereof, of tubular guides applied to the body over the slots and having upper open ends with a reinforced structure, a pivot device engaging the cover and having screw-stems extending 75 upwardly through the guides, the cover, and adjusting-nuts engaging the upper ends of the screw-stems and bearing on the upper open ends of the guides. 80
14. In a copying-bath, a body having a lower-drawer compartment, and a drawer constructed of a sheet-metal strip open at opposite sides and having the ends upturned and rebent toward the main body of the sheet, and reinforced devices inclosed in the bent ends 95 of the drawer, the latter being removably mounted in the said compartment. 90
15. In a copying-bath, a body having slots in opposite sides thereof, covering means for the slots, and a cover having a pivot device 100 extending loosely therethrough and formed with flat faces to fit in the said slots, the cover being adjustable.
- In testimony whereof I affix my signature in presence of two witnesses.
